UNITED STATES PATENT OFFICE.

HERBERT O. ROSS, OF ST. LOUIS, MISSOURI.

INDEX OR RECORD.

Application filed November 5, 1924. Serial No. 747,936.

This invention relates generally to indexes, records, lists, and the like and, more particularly, to a certain new and useful improvement in sectional indexes or records of the type that includes a plurality of separate so-called individual or record sections or cards.

My present invention has for its chief object the provision of an index or record of the type stated not only in which the several record-sections are adapted for engagement with a holder, but also in which the several record-sections are adapted for convenient interlocking engagement one with the other preferably in overlapping or imbricated arrangement, in such manner that the several record-sections collectively present a more or less readily visible substantially continuous record or sheet and in such manner also that one or more of the individual record-sections may be readily removed and replaced, whereby revision of and correction in the index or record may be effected with facility, convenience, and economy.

My present invention has for a further object the provision of a record or index of the type and kind stated which is compact and inexpensive in manufacture and maintenance, easily manipulated, and flexible in capacity, being readily increased and decreased in such regard, and eliminations and additions effected without destroying or affecting the remainder of the record or index.

And with the above and other objects in view, my present invention resides in the novel features of form, construction, arrangement, and combination of parts hereinafter described and pointed out in the claims.

In the accompanying drawings,

Figure 1 is a plan view of a sectional index or record embodying my invention;

Figure 2 shows in inverted plan an enlarged fragment of the index or record;

Figure 3 shows in enlarged perspective a fragment of one of the individual record-sections or cards;

Figure 4 shows in enlarged fragmental perspective a plurality of the individual record-sections or cards of Figure 3 in interlocked imbricated or overlapping relation;

Figure 5 shows in enlarged perspective a fragment of a modified form of individual record-section or card;

Figure 6 shows in enlarged perspective a plurality of the individual record-sections

or cards of Figure 5 in interlocked imbricated or overlapping relation;

Figure 7 also shows in inverted plan an enlarged fragment of the index or record, 60 illustrating the manner of locking and unlocking the several sections;

Figure 8 is a fragmental plan view of a modified form of sectional index or record embodying my invention; 65

Figures 9 and 10 show in enlarged perspective fragments of the individual record-sections or cards of the index or record of Figure 8; and

Figure 11 shows the record-sections or 70 cards of Figures 8 and 9 in flatwise registration for interlocking relation with the holder or back or with another similarly registering pair of individual record-sections or cards.

Referring now more in detail and by reference characters to the drawings, and first to the so-called preferred form of the index or record illustrated in Figures 1, 4 and 7, A, A, designate the main separate individual record-sections or cards of the index, each of 80 which cards or sections is constructed of somewhat flexible material, such for instance, as suitable paper, and each of which is of suitable predetermined length and breadth, for purposes of present description, the 85 length dimension of each section or card being the distance from side edge to side edge thereof and the breadth dimension of each section or card being the distance from upper to lower edge thereof. Each card or section A, as best seen in Figures 3 and 4, is formed suitably adjacent its opposed or opposite side or so-called vertical margins with a pair of substantially identical vertically aligned so-called obtuse-angular slots or 90 openings 1, 2, each of such slots 1, 2, comprising a portion 3 disposed vertically of the section and an upwardly and inwardly inclined portion 4. It may be here stated that the slots 1, 2, are suitably spaced vertically or 100 breadthwise of the card and also aligned in pairs horizontally or lengthwise of the card. At its opposite ends and at its upper margin each card A is cut away or recessed, as shown and formed with a pair of also horizontally aligned opposed tenons or tongues 5, which tongues bodily project lengthwise of the card beyond the plane of the vertically disposed portions 3 of the slots 1, 2, but preferably not beyond the plane of the side and upper 105 marginal edges of the card, the tongues 5 at their base or neck lying slightly inward-

ly of the plane of the portions 3 of the slots 1, 2, and at a suitable point within their length having a breadth dimension somewhat greater than the length dimension of said slot-portions 3, all as best seen in Figure 3.

In now initially assembling two or more of such individual record-sections or cards in index or record formation, a pair of the 10 cards, as best seen in Figure 4, are disposed in approximately flatwise superposed relation, preferably the one card suitably bodily flexed, and its tenons 5 inserted endwise within the upper horizontally aligned pair 15 of slots 1 of the other card. The upper pair of slots 1 of the then front or overlapping card then register with the lower pair of slots 2 of the then rear or overlapped card. A third card is then superposed flatwise upon the 20 first two cards, and the tenons 5 of such third card inserted endwise into the described registering upper slots 1 and lower slots 2 of the then two rear cards. The upper slots 1 of the then front or third card register with the 25 lower pair of slots 2 of the then intermediate or second card. A fourth card is now superposed flatwise upon the third card and the tenons 5 of such fourth card, in turn, inserted endwise into the then registering slots 1 and 30 2 of the third and second cards. When so inserted, the tongues or tenons 5 of the fourth or front card partly overlie the lower marginal end-portions 6 of the originally first and now rearmost card, as indicated at *x*, 35 Figure 7, and with the several cards so disposed in imbricated or overlapping relation, it will be noted that the rearmost card underlies the inclined portions 4 of the registering slots 1 and 2 of the second and third 40 cards directly in front thereof. With the several cards so arranged and connected, they are, as will be noted, disposed in an imbricated or overlapping series with the upper marginal portion *a* of each card exposed and 45 visible and with each card partly underlying and restricting the inclined portions 4 of the second registering pair of slots 1 and 2 of the cards in front thereof. The so inserted tongues 5 of the fourth card and the 50 said lower marginal end-portions 6 of the first card are now so relatively flexed as to dispose such marginal end-portions 6 of the first card over breadthwise extended or enlarged portions of the tongues 5 of the fourth 55 card, or, reversely, such extended portions of the tongues 5 of the fourth card are disposed under such marginal end-portions 6 of the first card, as indicated at *y*, Figure 7. With the tongues 5 of the fourth card so engaged with the first card, the several described cards are, as will be seen, detachably secured together in slot-restricting relation. The several cards are thus interlocked in an imbricated or overlapping series and 60 present, with a portion of each card exposed, a

substantially continuous, though sectional, sheet, convenient for the recording or indexing of names, data, information, and the like.

In a similar manner, a fifth card may be disposed upon the fourth card and interlocked at its inserted tongues 5 with the marginal end-portions 6 of the then second card, and in such manner and by additional individual cards or sections, the index or record may be extended and enlarged to meet any 75 particular requirements.

Preferably to facilitate handling of the connected or interlocked cards A and their insertion in a file, desk-drawer, or the like, I provide a unitary holder B comprising a sheet of suitable sheet material, such as, for instance, relatively heavy paper-board or light sheet-metal, folded upon itself intermediate its ends to provide a back section 7 and a front section 8. Sheet B when so folded is of suitable dimension, width and length, to approximately correspond with the length and the combined overlapped breadth of the several connected cards A, and as seen in Figure 1, front section 8 is preferably of reduced length relatively to back section 7 and is provided or formed longitudinally adjacent its opposed or opposite vertical margins with rows or series of slots or openings 9 similar in form to the card-slots 1, 2, the slots 9 being also equidistantly spaced and aligned horizontally in pairs. The slots 9 accommodate the convenient insertion of the tongues 5 of the cards A at the top or upper end of the connected or interlocked series, and the flap 8 thus functions to suspend the series of connected cards A hinged over and upon the back or main holder-section 7 for convenient handling and manipulation.

As will be noted, the cards A are of more or less extended breadth and provide considerable surface area for pertinent entries having to do with a particular index or record. In some instances or for certain requirements, separate individual record-sections or cards of reduced breadth are desirable, and hence I provide the cards C of Figure 5, which, as will be seen, are of less breadth and surface area than the cards A, but of substantially identical structure, with the exception that the cards C have merely one pair of tongue-accommodating slots, as, for instance, slots 1^a, instead of two pairs of such slots, as in the broader cards A. The cards C are also similarly connected and locked together, as best seen in Figure 6, initially the lower marginal end-portions 6 of the first card and the tongues 5 of the third card being interengaged, in like manner as described concerning the first and fourth cards A, to interlock the reduced or narrower cards C in a similar imbricated series, each succeeding and additional card C interlocking at its tongues 5 with the marginal end-portions 6 of an adjacent card C, and so on throughout the en-

largement or extension of the series in index or record formation.

Frequently it is also desirable that a particular index or record as a whole be of greater surface area relatively to the surface area of a record formed either by series of the cards A or C without an extended enlargement of the complete record. To meet and fill such requirement, I combine in a single index or record pairs of cards A and D, the card A of Figure 10 being like the card A of Figure 3 and the card D of Figure 9 being of identical structure with card A, but having an upper marginal portion d of greater breadth and hence surface area than the upper marginal portion a of the cards A. Then, in connecting the several cards A and D together in the formation or completion of an index or record, the cards A and D are disposed flatwise in pairs, registering at their slots and tongues and at their edges throughout, except at their unequal upper marginal portion a and d , when, as will be seen by reference particularly to Figure 11, a part of marginal portion d of the under and larger card D is exposed. Pairs of the cards A and D in such slot and tongue registration are then manipulated and connected together as units in the formation of the sectional record or index illustrated in Figure 8 in substantially identically the same manner as described in connection with the interlocking of a series of the single cards A in the formation of the sectional record of Figures 1 and 2, but I thus provide in the record of Figure 8 a record or index of substantially twice the number of cards or individual sections in the index or record of Figures 1 and 2 without extending the length of the combined or connected sections beyond a convenient size for easy handling and manipulation.

It will be evident that by disengaging the lower marginal portions 6 of a respective card or of a respective pair of slot and tongue registering cards from the tenons or tongues 5 of the next second or third adjacent single section or card or pairs of cards, as indicated in Figure 7, one or more of the single individual sections or cards or one or more of the registering pairs of cards may be readily removed and replaced substantially at any point in the connected series, and additions and eliminations in the index or record thus quickly accomplished, and, as stated, the record or index may be so broken at any desired point and again connected.

Normally, and as suspended from the holder section 8, portions only of the several cards are exposed and visible, but by suitable flexing of the respective connected cards, substantially the entire front surface area of each is presented for the entry of matters pertinent to the particular record, and by flexing the holder-section 8 together with the several connected cards parallel with the lower edges

of the several cards, or, as it might be described, breadthwise of the several connected cards, a greater portion of the area of each respective card is automatically exposed for ready visibility, whereby flexing or bending of the individual cards for such purpose is obviated. It will be evident, however, that the relative positions of the sections 7 and 8 of holder B may by hinged movement of flap 8 and its suspended record be reversed, when similarly the under faces of the several cards may be conveniently utilized for the reception of desired record or index entries.

My new index or record is exceedingly flexible, is inexpensive in manufacture and maintenance, is readily increased or decreased in size to meet requirements, is readily manipulated as to size and for corrections and additions, and provides a most efficient visibly continuous, though sectional, means for the compilation of information, data, names, and entries for various purposes.

I am aware that changes in the form, construction, arrangement, and combination of the several parts of my new sectional record or index may be made and substituted for those herein shown and described without departing from the nature and principle of my invention.

Having thus described my invention, what I claim and desire to secure by Letters Patent is:

1. A sectional record including a plurality of separate sections each provided with a pair of horizontally aligned and opposed tongues and a pair of horizontally aligned and opposed obtuse-angular slots and adapted for interengagement at said tongues and slots in an imbricated series.

2. A sectional record including a plurality of separate sections each provided with a pair of horizontally aligned and opposed tongues and a pair of horizontally aligned and opposed slots and adapted for interlocking engagement at said tongues and slots in an imbricated series with respective sections extending across and thereby restricting the slots of other respective sections.

3. A sectional record including a plurality of separate sections each provided with a pair of horizontally aligned and opposed tongues and a pair of horizontally aligned and opposed obtuse-angular slots and adapted for interlocking engagement at said tongues and slots in an imbricated series with respective sections extending across and thereby restricting the slots of other respective sections.

4. A sectional record including a plurality of separate sections each provided with a pair of horizontally aligned and opposed tongues and a pair of horizontally aligned oppositely disposed, obtuse-angular slots, portions of said slots being disposed vertically of the respective sections, said sections being adapted for interengagement at said tongues and slots

in an imbricated series, the tongues having at a point within their length a breadth greater than the length of the vertically disposed portions of said slots and one section being adapted to restrict the inclined portions of the slots of another section when said tongues and slots are in interengagement.

5. A sectional record including a plurality of separate sections each provided with a pair of horizontally aligned and opposed tongues and pairs of horizontally aligned oppositely disposed obtuse-angular slots, portions of said slots being disposed vertically of the respective sections, said sections being adapted for 10 interengagement at said tongues and slots in an imbricated series, the tongues having at a point within their length a breadth greater than the length of the vertically disposed portions of said slots and a respective section being adapted to restrict the inclined portions of slots of another respective section when said tongues and slots are in interengagement.

6. A sectional record including a plurality of separate sections, some of which sections 25 are of greater breadth than the other sections and each of said sections being provided with a pair of horizontally aligned and opposed tongues and a pair of horizontally aligned opposed slots, said sections being disposed in 30 tongue and slot registering pairs and adapted in such pair relation for interengagement at said tongues and slots in an imbricated series.

7. A sectional record including a plurality of separate sections, some of which sections 35 are of greater breadth than the other sections and each of said sections being provided with a pair of horizontally aligned and opposed tongues and a pair of horizontally aligned oppositely disposed obtuse-angular slots, portions of said slots being disposed vertically of the respective sections, said sections being disposed in tongue and slot registering pairs and each pair comprising one of said sections of greater breadth and one of said sections of 40 lesser breadth, said sections being adapted in such pair relation for interengagement at said tongues and slots in an imbricated series, the tongues having at a point within their length a breadth greater than the length of the vertically disposed portions of said slots and a respective pair of sections being adapted to restrict the inclined portions of slots of another respective pair of sections when the said tongues and slots are in interengagement.

55. 8. A sectional record including a plurality of separate sections, some of which sections are of greater breadth than the other sections and each of said sections being provided with a pair of horizontally aligned and opposed 60 tongues and pairs of horizontally aligned oppositely disposed obtuse-angular slots, portions of said slots being disposed vertically of the respective sections, said sections being disposed in tongue and slot registering pairs and 65 each of said pairs comprising one of said

sections of greater breadth and one of said sections of lesser breadth, said sections being and adapted in such pairs for interengagement at said tongues and slots in an imbricated series, the tongues having at a point 70 within their length a breadth greater than the length of the vertically disposed portion of said slots and a respective pair of sections being adapted to restrict the inclined portions of slots of another respective pair of sections 75 when the tongues and slots are in interengagement.

9. A sectional record including a plurality of separate sections, one of which sections is provided with a pair of horizontally aligned 80 obtuse angular slots, portions of said slots being disposed vertically of the respective sections, a third one of which sections is provided with a pair of horizontally aligned oppositely disposed tongues, and a second one of which sections is provided with both a pair of said tongues and a pair of said slots, said sections being adapted for interengagement at said tongues and slots in such relation that the third section overlaps upon the second section and the second section upon the first section, the tongues having at a point within their length a breadth greater than the length of the vertically disposed portions of said slots and the first section being adapted to restrict the inclined portions of the slots of the second section when said slots and tongues are in interengagement.

10. A sectional record including a plurality of separate sections, one of which sections is provided with a pair of horizontally aligned obtuse-angular slots, portions of said slots being disposed vertically of the respective sections, a third one of which sections is provided with a pair of horizontally aligned oppositely disposed tongues, and a second one of which sections is provided with both a pair of said tongues and a pair of said slots, said sections being adapted for interengagement at said tongues and slots in such relation that the third section overlaps upon the second section and the second section upon the first section, the tongues having at a point within their length a breadth greater than the length of the vertically disposed portions of said slots and the first section being adapted to extend across and thereby restrict the inclined portions of the slots of the second section when said slots and tongues are in interengagement, the first section being also adapted for marginal engagement with the inserted tongues of the third section for interlocking the several sections together.

11. A sectional record including a plurality of separate sections each provided with a pair of horizontally aligned and opposed tongues and a pair of horizontally aligned and opposed slots and adapted for cooperation in an imbricated series, the tongues and slots of one section being adapted for interengage- 125 130 135 140 145 150 155 160 165 170 175 180 185 190 195 200 205 210 215 220 225 230 235 240 ment with the slots and tongues of other sections and a respective section being adapted for marginal interlocking with the tongues of another respective section.

5 12. A sectional record including a plurality of separate sections each provided with a pair of horizontally aligned and opposed tongues and a pair of horizontally aligned and opposed obtuse-angular slots and adapted for 70 cooperation in an imbricated series, the tongues and slots of one section being adapted for interengagement with the slots and tongues of other sections and a respective section being adapted for marginal interlocking 75 with the tongues of another respective section.

13. A sectional record including a plurality of separate sections, one of which sections is provided with a pair of horizontally aligned 80 oppositely disposed obtuse-angular slots, portions of said slots being disposed vertically of the section, a fourth one of which sections is provided with a pair of horizontally aligned and opposed tongues, and a second one and a 85 third one of which sections are each provided with both a pair of said tongues and pairs of said slots, said sections being adapted for interengagement at said tongues and slots in such relation that the fourth section overlaps 90 upon the third section, the third section upon the second section, and the second section upon the first section with the upper pair of slots of the third section registering with the lower pair of slots of the second section, the 95 tongues having at a point within their length a breadth greater than the length of the vertically disposed portions of said slots and the first section being adapted to extend across and thereby restrict the inclined portions of 100 the registering slots of the second and third sections when said slots and tongues are in interengagement.

14. A sectional record including a plurality of separate sections, one of which sections is provided with a pair of horizontally aligned 105 oppositely disposed obtuse-angular slots, portions of said slots being disposed vertically of the section, a fourth one of which sections is provided with a pair of horizontally aligned and opposed tongues, and a second one and a third one of which sections are each provided with both a pair of said tongues and pairs of said slots, said sections being adapted for interengagement at said tongues and slots in such relation that the fourth section overlaps 110 upon the third section, the third section upon the second section, and the second section upon the first section with the upper pair of slots of the third section registering with the lower pair of slots of the second section, the tongues having at a point within their length a breadth greater than the length of the vertically disposed portions of said slots and the first section being adapted to extend across and thereby restrict the inclined por-

tions of the registering slots of the second and third sections when said slots and tongues are in interengagement, the first section being also adapted for marginal engagement with the inserted tongues of the fourth section for interlocking the several sections together. 120

15. A sectional record including a plurality of separate sections each provided with a pair of horizontally aligned and opposed tongues 75 and a pair of horizontally aligned oppositely disposed obtuse-angular slots, portions of said slots being disposed vertically of the respective sections, said sections being adapted for interengagement at said tongues and slots 80 in an imbricated series, the tongues having at a point within their length a breadth greater than the length of the vertically disposed portions of said slots and respective sections being adapted to extend across and thereby restrict the inclined portions of slots of other respective sections and respective sections being adapted for marginal engagement with the inserted tongues of respective sections for interlocking the several sections together. 85

16. A sectional record including a plurality of separate sections each provided with a pair of horizontally aligned and opposed tongues and pairs of horizontally aligned oppositely disposed obtuse-angular slots, portions of 90 said slots being disposed vertically of the respective sections, said sections being adapted for interengagement at said tongues and slots in an imbricated series, the upper pair of slots of respective sections, when the same 100 are in said relation, registering with the lower pair of slots of respective other sections, the tongues having at a point within their length a breadth greater than the length of the vertically disposed portions of said slots and respective sections being adapted to extend across and thereby restrict the registering inclined portions of slots of respective other sections and respective sections being adapted for marginal engagement with the inserted 110 tongues of respective other sections for interlocking the several sections together. 105

17. In a sectional record, a section marginally recessed upon its opposite side edges and provided with a pair of horizontally 115 aligned slots and at said recesses with a pair of horizontally aligned and opposed tongues.

18. In a sectional record, a section marginally recessed upon its opposite side edges and provided with a pair of horizontally 120 aligned and opposed obtuse-angular slots and at said recesses with a pair of horizontally aligned and opposed tongues.

19. A sectional record including a plurality of separate marginally recessed sections each 125 provided with a pair of horizontally aligned and opposed slots and at said recesses with a pair of horizontally aligned and opposed tongues and adapted for interengagement at said tongues and slots in an imbricated series.

- the tongues of each respective section being concealed by an adjacent section.
20. A sectional record including a plurality of separate sections each marginally recessed upon its opposite side edges and each provided with a pair of horizontally aligned and opposed obtuse angular slots and within said recesses with a pair of horizontally aligned and opposed tongues, said sections being adapted for interengagement at said tongues and slots in an imbricated series and when so engaged the tongues of each respective section being concealed by an adjacent section.
21. In a sectional record, a section provided with a pair of horizontally aligned and opposed tongues and a pair of horizontally aligned and opposed obtuse-angular slots, portions of said slots being disposed vertically of the section and the tongues having at a point within their length a breadth greater than the length of the vertically disposed portions of the slots.
22. A sectional record including a plurality of separate sections each provided with a pair of horizontally aligned and opposed tongues and a pair of horizontally aligned and opposed obtuse-angular slots and adapted for interengagement at said tongues and slots in an imbricated series, portions of said slots being disposed vertically of the respective sections and said tongues having at a point within their length a breadth greater than the length of the vertically disposed portions of said slots.
23. A sectional record including a plurality of separate sections each provided with a pair of horizontally aligned and opposed tongues and a pair of horizontally aligned and opposed obtuse-angular slots and having interengagement at said tongues and slots in an imbricated series, in combination with a back having a similar pair of slots for interengagement with the tongues of one of said sections.
24. A sectional record including more than two separate sections each provided with a pair of horizontally aligned and opposed tongues and a pair of horizontally aligned and opposed slots and adapted for interengagement at said tongues and slots in overlapping arrangement with one section marginally projecting over a portion of each of the tongues of a non-adjacent section.
25. A sectional record including more than two separate sections each provided with a pair of horizontally aligned and opposed tongues and a pair of horizontally aligned and opposed obtuse-angular slots and adapted for interengagement at said tongues and slots in overlapping arrangement with one section marginally projecting over a portion of each of the tongues of a non-adjacent section.
26. A sectional record including a plurality of separate sections each provided with a pair of horizontally aligned and opposed tongues and a pair of horizontally aligned and opposed slots and adapted for interengagement at said tongues and slots in an imbricated series, in combination with a back having a pair of slots for interengagement with the tongues of one of said sections.
27. In a sectional record, in combination with a back, of a plurality of record-sections jointed edgewise together in an imbricated series with an edge portion of each card exposed and visible, one of said sections having jointed connection with the back and the back being flexible breadthwise of said sections, whereby on flexing the connected back and cards an additional portion of the area of each respective card is exposed.
28. In a sectional record, in combination with a back, of a plurality of record-sections having tongue and slot interengagement and disposed in an imbricated series with an edge portion of each card exposed and visible, one of said sections having tongue and slot interengagement with said back and the back being flexible breadthwise of said sections, whereby on flexing the connected back and cards an additional portion of the area of each respective card is exposed.

In testimony whereof, I have signed my name to this specification.

HERBERT O. ROSS.
